FIG-6

FIGURE 1 is a top perspective view of a combined packaging box and serving tray showing my new design; FIGURE 2 is a top plan view thereof;

The basket weave pattern on the design is continuous on all the outer walls except on the bottom wall and tear strip portion which are plain and unornamented.

I claim:

The ornamental design for a combined packaging box and serving tray, as shown and described.
